(57) **CLAIM**

An ornamental design for a base for holding pipette tip container, as shown and described.

DESCRIPTION

FIG. 1 is a front right-side perspective view showing a first embodiment of a base for holding pipette tip container in accordance with the new design;

FIG. 2 is a another top perspective view thereof;

FIG. 3 is a rear and top perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a front right-side perspective view showing a second embodiment of a base for holding pipette tip container in accordance with the new design;

FIG. 11 is a another top perspective view thereof;

FIG. 12 is a rear and top perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof; and,

FIG. 18 is a bottom plan view thereof.

The dashed lines in the drawings depict portions of the base for holding pipette tip container that form no part of the claimed design.
